(57) **CLAIM**

The ornamental design for a hoverboard, as shown and described.

DESCRIPTION

FIG. 1 is a perspective view of a hoverboard showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view taken from the right side of FIG. 1; and,

FIG. 10 is an enlarged partial view taken from the middle of FIG. 1.

The broken lines in the drawings are for the purpose of illustrating portions of the hoverboard that form no part of the claimed design. The dash-dot broken lines represent the boundaries of the enlarged partial views of FIGS. 9 and 10 and form no part of the claimed design.
